Primary Examiner — Antoine D Davis(74) *Attorney, Agent, or Firm* — Hartman & Citrin LLC(57) **CLAIM**

The ornamental design for a tension meter, as shown and described.

DESCRIPTION

FIG. 1 is a front perspective view of a tension meter, where the broken line showing a linear element, the broken lines showing three pulleys through which the linear element is routed, the broken lines showing fasteners, and the broken lines showing a handle are for the purpose of illustrating portions of the article and form no part of the claimed design; FIG. 2 is a front view of the tension meter, where the broken line showing a linear element, the broken lines showing three pulleys through which the linear element is routed, the broken lines showing fasteners, and the broken lines showing a handle are for the purpose of illustrating portions of the article and form no part of the claimed design; FIG. 3 is a rear view of the tension meter, where the broken line showing a linear element, the broken lines showing fasteners, and the broken lines showing a handle are for the purpose of illustrating portions of the article and form no part of the claimed design; FIG. 4 is a left side view of the tension meter, where the broken line showing a linear element, the broken lines showing a pulley through which the linear element is routed, the

broken lines showing fasteners, and the broken lines showing a handle are for the purpose of illustrating portions of the article and form no part of the claimed design;

FIG. 5 is a right side view of the tension meter, where the broken line showing a linear element, the broken lines showing a pulley through which the linear element is routed, the broken lines showing fasteners, and the broken lines showing a handle are for the purpose of illustrating portions of the article and form no part of the claimed design;

FIG. 6 is a bottom view of the tension meter, where the broken line showing a linear element, the broken lines showing two pulleys through which the linear element is routed, the broken lines showing fasteners, and the broken lines showing a handle are for the purpose of illustrating portions of the article and form no part of the claimed design; and,

FIG. 7 is a top view of the tension meter, where the broken line showing a linear element, the broken lines showing a pulley through which the linear element is routed, the broken lines showing fasteners, and the broken lines showing a handle are for the purpose of illustrating portions of the article and form no part of the claimed design.
